TURPENTINE CUP

Filed April 21, 1930

UNITED STATES PATENT OFFICE

HARRY FULENWIDER AND HARRY NORRIS, OF SAVANNAH, GEORGIA, ASSIGNEES TO SOUTHERN STATES IRON ROOFING COMPANY, OF SAVANNAH, GEORGIA, A CORPORATION OF GEORGIA

TURPENTINE CUP

Application filed April 21, 1930. Serial No. 446,022.

This invention relates to improvements in metallic or other receptacles, and more particularly to an improved form of turpentine cup used for collecting the resinous gum from pine trees.

An object of our invention is to provide an improved form of turpentine cup folded from a single sheet of metal, and making the folds in the same on the inside of the cup instead of on the outside, as is the usual practice, thereby effecting a decided saving in material used since a shorter blank may be used where the folds are on the inside than where the folds are on the outside of the cup.

Another object of our invention is to provide an improved folded metal turpentine cup formed from a single blank of material, and so arranged that the material usually trimmed off from the top of the cup serves as a reinforcing means or is turned over to house short reinforcing wires placed at the opposite ends of the cup.

A further object of the invention is to provide a folded turpentine cup formed from a single blank of material, in which one or more water drains are formed in each end of the cup, thereby permitting the surplus water which may accumulate in the cup to drain therefrom without allowing the resinous gum to escape from the cup.

A still further object of the invention is to provide an improved form of turpentine cup formed from a single blank of material, which will be highly efficient in use and quite inexpensive to manufacture.

Other objects will appear as the description proceeds.

In the accompanying drawings which form a part of our application,

Figure 1 is a perspective view of our improved turpentine cup;

Figure 2 is an end view of the turpentine cup;

Figure 3 is a sectional view taken on the line 3-3 of Figure 2;

Figure 4 is a sectional view taken on the line 4-4 of Figure 2, and

Figure 5 is a perspective view of one of the reinforcing bands used at the opposite ends of our turpentine cup.

Like characters of reference are used throughout the following specification and the accompanying drawings to designate corresponding parts.

In carrying out our invention, we form our improved turpentine cup 1 from a single blank of sheet metal by folding the same so that the folds will be on the inside of the cup and at the opposite ends thereof, as clearly illustrated in Figures 1 and 3 of the drawings.

The cup 1 will be provided with a bottom 2, side walls 3 and end walls 4, and will be substantially rectangular in shape, being slightly larger at the top than at the bottom. The end walls 4 of the cup 1 are provided with spaced S-folds 5 on the inside of the cup, and the outer layer of the material in each of the said S-folds is crimped to provide the spaced vertical water passages 6, having discharge outlets 7 at the top of the passages on the outside of the cup, and inlet ports 8 at the lower ends of the passages on the inside of the cup, as clearly illustrated in Figure 4 of the drawings. The purpose of the passages 6 is to permit the draining of any water accumulated in the cup and to prevent the resinous gum from escaping from the cup.

The material from which the cups are formed is notched at the upper corners 9 to provide an anchorage for the wire reinforcing bands 10 which are disposed at the opposite ends of the cup and extend along the opposite sides thereof and terminate in the prongs 11 which are adapted to be received within the lock sockets 12 formed through the side walls of the cup, as clearly illustrated in Figure 1 of the drawings. The ends of the blank, after the cup is formed, are bent outwardly and over the reinforcing bands 10 which positively support the same at the ends and opposite sides of the cup. The bent over beads 13 serve to additionally reinforce the cup, and to hold the same in its proper shape at all times. It is the material from which the beads 13 are formed that is usually cut off as waste, when the folds at the ends of the cup are made on the outside.

From the foregoing description, it is believed that the specific reinforcing bands and

their supporting beads are new in the particular use, also, it is believed that the folding of the **S**-folds on the inside ends of the cups is novel. Furthermore, the drain grooves in the **S**-folds are a decided step in advance and are believed to be novel.

Many minor changes in details of construction may be resorted to without departure from the spirit of the invention.

Having thus described our invention what we claim as new and desire to secure by Letters Patent of the United States is:

1. A turpentine cup formed from a single blank of material comprising a bottom, sides and ends, and **U**-shaped reinforcing bands secured at the opposite ends of said cup and positively engaging the side walls thereof. 75
2. A turpentine cup formed from a single blank of material comprising a bottom, sides and ends, said ends being formed with **S**-folds on their inner surfaces, and **U**-shaped reinforcing bands secured at the opposite ends of said cup and positively engaging the side walls thereof. 80
3. A turpentine cup formed from a single blank of material comprising a bottom, sides and ends, said ends being formed with **S**-folds on their inner surfaces, spaced beads formed at the opposite sides and ends of said cup, and **U**-shaped reinforcing bands secured in said beads and having laterally extending securing means formed at their extremities adapted to be received in the side walls of said cup. 85
4. A turpentine cup formed from a single blank of material comprising a bottom, sides and ends, said ends being formed with **S**-folds on their inner surfaces and with vertically disposed drain passages, spaced beads formed at the opposite side and ends of said cup, lock sockets formed in the opposite sides of said cup, and **U**-shaped reinforcing bands secured in said beads and having laterally extending securing means formed at their extremities adapted to be received in said sockets. 90
5. The combination as set forth in claim 4, and an inlet port for each drain passage located at the lower end thereof and on the inside of the cup, and an outlet port at the upper end thereof and on the outside of the cup. 95
6. A turpentine cup formed from a single blank of material comprising a bottom, sides and ends, said ends being formed with spaced alined **S**-folds on the inside of said cup, the outer folds of said **S**-folds being formed to provide vertically alined drain passages having their inlets on the inside of the cup and at the lower ends of said passages, and their outlets on the outside of said cup and at the top of said passages. 100
7. A turpentine cup formed from a single blank of material comprising a bottom, sides and ends, said ends being formed with **S**-folds on their inner surfaces, and a reinforce- 105
